A. KRAUTH,
PAPER PERFORATOR.

APPLICATION FILED FEB. 24, 1915.

1,199,193.

Patented Sept. 26, 1916.

UNITED STATES PATENT OFFICE.

ALBERT KRAUTH, OF HAMILTON, OHIO, ASSIGNOR TO KRAUTH & BENNINGHOFEN, A COPARTNERSHIP COMPOSED OF ALBERT KRAUTH AND CHRISTIAN BENNINGHOFEN, OF HAMILTON, OHIO.

PAPER-PERFORATOR.

1,199,193.

Specification of Letters Patent. Patented Sept. 26, 1916.

Original application filed July 1, 1912, Serial No. 706,975. Divided and this application filed February 24, 1915. Serial No. 10,832.

To all whom it may concern:

Be it known that I, ALBERT KRAUTH, a citizen of the United States, and residing at Hamilton, in the county of Butler and 5 State of Ohio, have invented a new and useful Improvement in Paper-Perforators, of which the following specification is a full disclosure.

My invention relates to an improvement 10 in perforating devices primarily rotary as to their mode of operation, in which capacity they may be conveniently embodied conjunctively with say a rotary printing press, operating upon web lengths of material. 15 From such particular use the disclosure herein is divisional from an application filed by me July 1, 1912, Serial No. 706,975, for improvement in printing presses bearing Patent No. 1,132,191 dated Mar. 16, 20 1915, and to avoid a complete reiteration of the subject-matter of said application in such designated particular use reference should be had to said application or for any 25 omissions herein to impart a complete disclosure of the invention.

As a perforating apparatus, *per se*, the invention has as an object to provide coacting members relatively positively rotative for coöperation and registry of their respective punch and die elements for making definitely spaced perforations, longitudinally aligned, through the material fed between the members. The accuracy of the perforation spacing and sharpness of cut are features of 30 35 prominence, and in particular for perforating strips of paper for manifolding machines, in which the perforations serve for registry and arresting purposes in withdrawing or delivering the paper in measured sheet lengths.

A further object of the invention relates to means for mounting and adjusting the punch members of coacting rotary perforating devices, with micrometric precision 45 to delicately regulate the depth of intermesh with their companion members, to obviate injury to the parts from relative differential angular velocity, or injury to the perforation outline in the material perforated.

50 Further objects and advantages of the invention will be more fully disclosed in the description of the accompanying drawings forming a part of this specification and in such drawings like characters of reference

denote corresponding parts throughout the 55 several views of which:—

Figure 1 is a central vertical section through the perforating apparatus. Fig. 2 is an elevation of one end of the mechanism shown in Fig. 1. Fig. 3 is an enlarged detail section through the punching or die members at their point of registration. Fig. 4 is a section on line 4—4 Fig. 1.

As this invention is primarily directed to mechanism for perforating paper or other 65 sheet-like material in a continuous performance with the feed of the material, it is obvious that in producing measured perforation spacing, coöordination must exist between the material fed and perforator rotation ratios, but as there are geometric timing factors not materially relevant to the invention herein no feeding devices are herein disclosed, and for such, reference is directed to said aforesaid application, although any 70 well-known feeding means may equally apply.

A pair of side frames 1, 2, comprise a support for the perforating devices, and each frame has suitable bearings for supporting 80 and journaling the shaft 3. The shaft 3 has a gear 4 loosely mounted thereon adapted to be frictionally clutched thereto. The gear 4 constitutes the driving member for the perforating devices and may receive its power 85 from any suitable source. Any well-known means may be employed for controlling the rotation of shaft 3, the means herein shown being constructed as follows:

The inner periphery of the gear 4 has an 90 annular inclined or tapered surface 5 adapted to be engaged by a correspondingly tapered friction disk 6 keyed and splined upon the shaft 3. A screw rod 7 is screw-threaded into the end of the shaft 3, and is 95 provided with an annular flange 8. One side of the flange engages with a collar 9 fixed to the hub of disk 6 and the opposite side of the collar is engaged by a hand wheel 10 secured upon the screw-rod 7. In 100 revolving the hand wheel 10 the disk 6 is fed either into or out of its clamping engagement with the surface of the gear 4 for controlling the rotation of shaft 3. The hand wheel may be provided with means 105 for rigidly locking the same against rotation for a precautionary measure, although not absolutely essential. The shaft 3 has a

gear 11 fixed thereon in mesh with a gear 12 fixed upon the shaft 13, which is journaled in the bearing members 14, 15 secured upon the side frames 1 and 2.

5 The gears 11 and 12 are adjacent one of the side frames and a second set of gears 16, 17 is provided upon the opposite side adjacent the frame 1 to equalize the transmission between said shafts for insuring positive coördinate rotation thereof and as far as possible avoid flexing and distorting strains upon the shafts which might interfere with the accurate registration of the perforating devices mounted upon and revolved with said shafts. The shaft 3 is longitudinally adjustable within its bearings for registering and alining the perforating devices micrometrically, and is accomplished by the following mechanism: The end of 20 the shaft 3 is studded and screw-threaded to receive a thimble or hub portion of the hand wheel 18 slidable thereon. The periphery of the hub is screw-threaded and engages with a flange 19 concentric with the shaft 3 and secured to the side frame 2. The end of the shaft has a collar 20 screw-threaded thereon to provide an abutment for the hub of the hand wheel 18, the opposite end of the hub engaging with the shaft shoulder. Upon revolving the hand wheel 18, the shaft may be moved longitudinally to any desired degree within a predetermined range.

35 As shown the punch and die elements are secured upon or within disks or circumferential drums or carriers arranged in pairs or sets with each set suitably spaced from the adjacent set when more than one series is employed. The number and relative spacing of the perforating devices is optional depending upon the particular job. The construction is such as to provide rigidity when the shafts extend a considerable length between bearings, to avoid flexing of the 40 shafts between the bearings, which if permitted to any considerable degree is detrimental to making a clear cut perforation. Additional safe-guard against shaft flexing is made by providing tie-bars 21 spanning 45 the gap between the bearings and connected at their ends respectively to the bracket plates 14 and 15. The shaft 3 carries, as may be herein designated, the die members, while shaft 13 carries the punch members, 50 although they may serve equally as well conversely.

55 The drawings illustrate a plural series of punch and die members and circumferential carriers therefor, and being the duplicate of one another the description will be confined to one set. The carriers disclosed are of disk form arranged in integrally 60 united pairs of convenience for a particular use, but the carriers may be variously modified within the aspect of this invention, in

an arrangement for perforating the material in lines longitudinal of its width.

70 The die supporting carrier 22 is fixed at a predetermined location concentrically upon the shaft 3 circumferentially, is provided with the die plate 23, seated within notches formed in the periphery of the carrier 22, and suitably secured thereto by screws, having its punch aperture alined with the clearance apertures 24 radially bored through the carrier, providing a discharge sprocket for the punchings. The die plates show two punch apertures coplanar for definite perforator width spacing, with two plates diametrically opposed upon the 80 carrier circumferentially for predetermined longitudinal spacing.

85 The punch supporting carrier 25 fixed upon the shaft 13 is of similar design as its companion carrier 22 on shaft 3, and in coplanar alinement therewith. It is provided with punch members corresponding in number to the dies on carrier 22 and in coordinate arrangement for progressive registry and coöperation. Each punch 90 comprises a tubular member 26 fitting into a radial orifice in the carrier, and projecting from the periphery of the carrier the desired degree for a proper entry depth or mesh into a registering die aperture of the 95 carrier 22. Thus when the punch or tubular member 26 projects beyond the point of tangency of the carrier circumference, which tangent point herein is assumed as being at the die entrance, the angular velocity of the 100 punch exceeds the die, by reason of the difference in their radius.

105 The die is very shallow and divergently undercut to enlarge its area beyond the die walls for cutting discharge clearance. The punch penetration into the die is also minute and to a degree which will insure satisfactory perforating without material variance in the comparative cutting areas of the members and at the same time permit free 110 rolling coöperation. This requires a delicate setting of either one of the members and is herein accomplished by rendering the punch members adjustable. The tubular punch 26 co-axially receives a set screw 27, 115 which threads therethrough adapting the set screw to engage the base of the carrier punch receiving the bore for varying the reach of the punch, in adjusting the punch radially to any degree required.

120 The periphery of the carrier is notched adjacent a punch receiving bore to provide a clearance for the screw 28 transversely engaging the punch for rigidly clamping the punch in any adjusted position.

125 From the foregoing it will be apparent that I provide coacting rotative perforator carriers with radial punch and die members rigidly located thereon, the members registering or meshing to a degree which will 130

not interfere with the rolling travel of the carriers or require enlargement of either member relatively.

The punch 26 is materially strengthened by the screw 27, as it provides an inner core of different tensile strength and tenacity than the tubular portion, and its construction also provides a recess in the cutting end of advantage in sharpening or grinding and perforating.

Having described my invention, I claim:—

1. In a machine of the classs described, a pair of rotative perforator carriers for respectively coöperatively supporting punch and die members, of a tubular punch member radially supported with one of said carriers, and a screw concentrically engaged within said punch member adapted to project through the same to engage a seat in said carrier for adjusting the reach of said punch member.

2. In a machine of the class described, a pair of rotative perforator carriers for re-

spectively coöperatively supporting punch and die members, of a tubular punch member 25 radially supported with one of said carriers, a screw concentrically engaged within said punch member adapted to project through the same to engage a seat in said carrier for adjusting the reach of said punch 30 member, and means for rigidly clamping said punch member within its carrier.

3. In a device of the class described, a punch support, a tubular punch member secured within said support, and an adjustable core member within said punch member for varying the reach of said punch member.

In witness whereof, I hereunto subscribe my name, as attested by the two subscribing 40 witnesses.

ALBERT KRAUTH.
